(57) CLAIM

The ornamental design for a microscope, as shown and described.

DESCRIPTION

FIG. 1 is a front perspective view of a microscope showing my new design;

FIG. 2 is a front view of the microscope shown in FIG. 1;

FIG. 3 is a rear view of the pouring lid shown in FIG. 1;

FIG. 4 is a right side view of the microscope shown in FIG. 1;

FIG. 5 is a left side view of the microscope shown in FIG. 1;

FIG. 6 is a top view of the microscope shown in FIG. 1;

FIG. 7 is a bottom view of the microscope shown in FIG. 1; and,

FIG. 8 is a rear perspective view of the microscope shown in FIG. 1.

The broken lines showing of various portions of the microscope are for illustrative purposes and form no part of the claimed design.
